CLAIM

The ornamental design for a media display device, as shown and described.

DESCRIPTION

FIG. 1 is a front elevation view of a media display device. A rear elevation view is omitted because it is identical with the front elevation view.

FIG. 2 is a top plan view thereof.

FIG. 3 is a bottom plan view thereof.

FIG. 4 is a right side elevation view thereof. A left side elevation view is omitted because it is identical with the right elevation view; and,

FIG. 5 is a perspective view thereof.

The oblique lines in the drawings indicate display screens of the media display device.
